UNITED STATES PATENT OFFICE.

LEWIS NIXON, OF NEW BRUNSWICK, NEW JERSEY.

PERCUSSION-FUSE.

1,311,835.

Specification of Letters Patent. Patented July 29, 1919.

Application filed March 29, 1917. Serial No. 158,280.

To all whom it may concern:

Be it known that I, LEWIS NIXON, a citizen of the United States, residing at New Brunswick, in the county of Middlesex and

5 State of New Jersey, have invented certain new and useful Improvements in Percussion-Fuses; and I do hereby declare the following to be a full, clear, and exact description of the invention, such as will enable 10 others skilled in the art to which it appertains to make and use the same.

My present invention relates to improvements in percussion fuses intended more especially for bombs to be dropped from 15 aeroplanes, or to be thrown from trench mortars, in which there is comparatively low velocity imparted to the projectile when the bomb is launched, and for hand grenades.

My invention is intended to provide a 20 percussion fuse which will explode the bomb irrespective of the point of impact, which in other words is effective whether the bomb strikes nose first, breech first, or sidewise, on impact.

25 My invention comprises broadly a spring impressed plunger, which is locked in place by a loose trigger, and the trigger is rigidly held in the safety position by certain locking means, which will be hereinafter described, but which are automatically released on the launching of the projectile, leaving the trigger free to act when the projectile strikes the target.

30 My invention will be more fully understood after reference to the accompanying drawings, in which:

Figure 1 is a side elevation of the complete fuse with the removable cap released.

Fig. 2 shows a central vertical section 40 through the fuse when in the safety position, parts being shown in elevation.

Fig. 3 shows a section along the line 3—3 of Fig. 2 and looking in the direction of the arrows, the cap, plug and tape being omitted.

45 Fig. 4 is a detail showing an interior view of the cap, with part of the tape protruding therefrom.

Fig. 5 is a detail showing in perspective the safety pin; and

50 Fig. 6 is a detail showing the trigger in perspective.

Like parts are indicated by corresponding reference letters throughout the several views.

55 A represents the fuse stock, which is closed at the forward end by the screw plug B,

carrying the primer C and the detonator D. This plug B is screw threaded as at b to receive the booster E, shown in dotted lines in Fig. 1.

The fuse stock A is provided with screw threads a to go into the shell of the projectile, and is also provided with the head A' having a chamber A^o, into which projects the stem of the plunger F. This plunger is 65 provided with the usual firing point f and is normally pressed forward to the firing position by the spring G.

The stem of the plunger is provided with an annular notch f', adapted to engage the 70 curved rib h on the trigger H. This trigger has a weighted arm h². The arm h' of the trigger is tapered slightly as at h^o at the back to engage in the tapered notch i of the locking pin I, which locking pin has a curved 75 back I' in the form of a plate adapted to fit in a countersunk groove a' in the fuse stock A, as shown in Fig. 3.

This locking pin I projects through the screw plug L, screwed into the side of the 80 fuse stock, and its back I' is normally pressed outward by the spring K mounted in a recess in the plug L, as shown in Fig. 2. The locking pin is normally held in engagement with the trigger against the action of 85 the spring K by suitable means such as a tape M wrapped around the head A' of the fuse stock, and having its free end passing through the slot n of the cap N, where it is held in place by suitable clamping piece N'.

90 This cap is adapted to slip over the head of the fuse stock and is detachably connected thereto by the screw P, having the butterfly head P', which screw engages in the block O screwed in the outer end of the fuse stock.

95 The parts are shown in the safety position in Fig. 2, and it will be obvious from inspecting said figure that the locking pin I will hold the trigger H in engagement with the stem of the plunger so that the plunger cannot fly forward under the action of the spring G.

100 The screw P will hold the cap N securely on the fuse stock, when the fuse is in the safety position. In order to prime the fuse 105 simply remove the screw P.

Now, when the projectile is thrown, the cap N, being more or less loose on the fuse stock, will tend to slip off therefrom, owing to the pressure of the air on its forward 110 face; and this pressure may be increased by flaring the edges of the cap somewhat as

- at n' . As soon as the cap slips off of the fuse stock, it will begin to unwind the tape M, and as soon as the tape is unwound, the spring K will throw the locking pin I backward, releasing the trigger, but which will be still held in place by the engagement of the lug h in the annular groove f'; but as soon as the projectile strikes the target no matter in what direction it may strike, the 10 weighted end h² of the trigger will shake the trigger loose and the spring G will throw the plunger F forward, exploding the primer, which will explode the detonator, and thereupon explode the bomb:
- 15 It will thus be seen that the fuse is absolutely safe so long as the cap is on, and that the cap can not come off until the screw P is removed; but when the cap comes off and unwinds the tape, the fuse will be fully 20 armed and will explode when striking any solid object, no matter from what direction the impact may occur.

Any suitable tape may be used, such as cloth, thin steel, or the like, or the winding 25 may be of wire or other material, the fundamental idea being that there is a detachable weight attached to the fuse stock by a flexible connection, which will unwind or become loose after the projectile has been thrown, 30 and when unwound, will release the locking pin and will arm the fuse.

It will be obvious that various modifications might be made in the herein described 35 apparatus, and in the construction, combination and arrangement of parts, which could be used without departing from the spirit of my invention.

Having thus described my invention, what I claim and desire to secure by Letters 40 Patent of the United States is:

1. In a fuse for projectiles of the character described, the combination with a fuse stock and a primer mounted therein, the said fuse stock having a chambered head, and a cap 45 loosely mounted on said head, of a spring impressed plunger mounted in said fuse stock and having its stem projecting into said chambered head, a trigger engaging said stem, a locking pin normally holding 50 said trigger in engagement with said stem,

and means for holding said locking pin in engagement with said trigger and for automatically releasing same, comprising a spring normally tending to throw said locking pin out of engagement with said trigger, and a flexible strip wound over said head and said locking pin and having its outer end secured to said cap, substantially as described. 55

2. In a fuse for projectiles of the character described, the combination with a fuse stock and a primer mounted therein, the said fuse stock having a chambered head, and a cap loosely mounted on said head, of a spring impressed plunger mounted in said fuse stock and having its stem projecting 60 into said chambered head, a trigger engaging said stem, a locking pin normally holding said trigger in engagement with said stem, and means for holding said locking pin in engagement with said trigger and for automatically releasing same, comprising a spring normally tending to throw said locking pin out of engagement with said trigger, and a flexible strip wound over said head and said locking pin and having its outer end secured to said cap, substantially as described. 65

3. In a fuse for projectiles of the character described, the combination with a fuse stock and a primer mounted therein, of a spring impressed plunger mounted in said fuse stock, a trigger engaging said plunger, a locking pin normally holding said trigger in engagement with said plunger, means for holding said locking pin in engagement with said trigger and for automatically releasing same, comprising a spring normally tending to throw said locking pin out of engagement with said trigger, a flexible strip wound over said fuse stock and normally holding said locking pin against the action of said spring, and means 70 automatically operated when the projectile is thrown for causing said strip to unwind thereby releasing said locking pin, substantially as described. 75

In testimony whereof I affix my signature.

LEWIS NIXON.
